UNITED STATES PATENT OFFICE.

HARRY M. STEVENS, OF SCHENECTADY, NEW YORK, ASSIGNOR TO GENERAL ELECTRIC COMPANY, A CORPORATION OF NEW YORK.

SWITCH-OPERATING MECHANISM.

1,176,616.

Specification of Letters Patent. Patented Mar. 21, 1916.

Application filed March 18, 1913. Serial No. 755,139.

To all whom it may concern:

Be it known that I, HARRY M. STEVENS, a citizen of the United States, residing at Schenectady, in the county of Schenectady, 5 State of New York, have invented certain new and useful Improvements in Switch-Operating Mechanism, of which the following is a specification.

My invention relates to switches for opening and closing an electric circuit, and more particularly to switches which control circuits carrying a large amount of energy and which automatically trip free from the handle or actuating member when the conditions in the controlled circuit are abnormal.

The parts of a switch suitable for controlling circuits carrying large amounts of energy are so heavy that a good deal of force is required to close the switch, and when closed a correspondingly large force or thrust is exerted in a direction which tends to open the switch. The parts which retain the switch in closed position must resist this thrust and must therefore be of rugged construction. In a switch which trips free from the handle this thrust is resisted by a normally positive collapsible connection between the operating handle and the switch mechanism. This connection must remain rigid and positive during the movement of the operating handle toward switch closing position, but should also be sensitive to the action of the tripping mechanism which causes the connection to collapse and release the switch from the handle when an abnormal condition, such as an overload, exists on the line. Unless the collapsible connection is sensitive the tripping mechanism must be made so large and powerful that much energy will be wasted in it.

One object of my invention is the provision of a rugged device or normally positive collapsible connection which positively and firmly connects the switch mechanism to the operating handle while the switch is being closed, but becomes very sensitive and easily operated to release the switch from the handle by the time the switch is closed, so that a small trip coil can automatically release the closed switch from the handle. To this end, I prefer to utilize the force exerted by the operator, to bring about marked increase in the sensitiveness of the normally positive connection when the switch is substantially closed. To accomplish this result I prefer

to partially disable or collapse the connection but prevent the total disabling or collapse of it by a sensitive device which responds to the action of the tripping coil and permits the connections to collapse completely upon the occurrence of an abnormal condition on the circuit.

Another object of my invention is the provision of means for disabling or collapsing the normally positive connection by an initial opening movement of the operating handle, thereby protecting the operator from injury by the handle as the switch opens and at the same time making it possible to leave the operating handle where it is out of the way.

Other objects and purposes of my invention will appear in the specification and the novel features will be particularly pointed out in the appended claims.

For a better understanding of my invention, reference may be had to the accompanying drawings, in which—

Figure 1 is a front elevation of the operating handle and the parts for connecting the handle to the mechanism of the switch; Fig. 2 is a vertical section taken on Fig. 1 and showing the handle in switch closing position; Fig. 3 is a view similar to Fig. 2 showing the normally positive connection between the handle and the operating mechanism of the switch disabled or collapsed by an initial switch opening movement of the handle; Fig. 4 is a vertical section on Fig. 1, but with the switch open and the handle swung through an angle of 180 degrees from the position shown in Fig. 1; and Fig. 5 shows the switch as installed.

Referring to the drawings, in which I have illustrated one embodiment of my invention, and first to Fig. 5, A indicates the switch, B the operating lever or handle, C the panel on which the handle and the parts co-operating therewith are mounted, and D the connections between the operating handle and the switch. I have here illustrated my invention in connection with an oil switch having an oil tank 1 suspended from the switch frame 2, which is secured at one end to the support 3. The other end of the frame is supported by a standard 4, which rests on the floor or base 5. Fiber thimbles 6 for the leads are set in insulating bushings 7, which carry fixed contacts at their lower ends, as usual in the art. Vertically mov-

able bridging contacts coöperate with the fixed contacts on the lower end of the insulators 7, and are connected to a crossbar or yoke 8 which is raised to close the switch and is lowered to open it. This yoke is raised and lowered by an arm 9, of which the end connected to the yoke is compelled to move up and down in a straight line by a parallel motion consisting of a system of links 10. The arm 9 is actuated through the parallel motion 10, the links 11, 12 and 13, and bell crank levers 14, 15 and 16, from a link 17 located in some convenient place, preferably upon panel C. It will be seen that to raise the yoke 8 and move the switch actuating mechanism to close the switch, the link 17 is moved to the right, and that when the switch is in the closed position the weight of the movable parts of the switch urges the link 17 toward the left.

As best shown in the other figures, especially Figs. 2 and 3, the outer end of the link 17 extends through an opening in an escutcheon plate 18 mounted on the panel C and is connected by a pivot 19 to an actuating lever or member 20. In the particular embodiment of the invention shown, this member 20 has the form of a bell crank lever, and is bifurcated, the two forks being pivoted on arbors 21 mounted in brackets 22 extending outwardly from the escutcheon plate 18. The link 17 and the member 20 form an actuating toggle which is straightened as the member 20 is swung about the arbor 21 in a clockwise direction into the position shown in Fig. 2.

The free end of the member 20 is formed into a solid block provided with a plane surface 23 which coöperates with a disengageable member or operating arm 24 on the operating handle. This disengageable member is carried between the two forks, b, b, of the operating handle B, which is also bifurcated and pivoted on the arbors 21. The disengageable member or arm 24 is also bifurcated, and I have here in fact illustrated the same as composed of two separate members which are pivoted at 25 to the handle and connected at their outer ends by a pin 26 on which is mounted a roller 27 adapted to engage the plane surface 23 on the lever 20 of the toggle. This plane surface on the lever 20 is so designed that a perpendicular from the pivot 25 of the member 24 to this plane surface will fall within the plane when the roller 27 is in engagement with the same, as shown in Fig. 2. The free end of the member 24 is urged toward the pivot of the operating handle by a spring 28, one end of which engages a web 29 on the handle. The pin 26 extends in both directions considerably past the two forks b b of the operating handle, and its ends engage two lugs 30 which are located on the back faces of the forks b b of the handle and

thereby limit the movement of the member 24.

When the switch is in open position, the position of the parts corresponds to that shown in Fig. 4. When the operating handle is moved to close the switch and to a position where the roller 27 engages the surface 23, as shown in dotted lines in Fig. 4, the parts are so designed that the pressure exerted by the roller on the plane surface tends to move the roller along the plane surface toward the stops 30. This tendency of the roller 27 to move toward the stops 30, forces the ends of the pin 26 against the stops on the handle and locks the handle very firmly to the lever 20. When the operating lever or handle, therefore, is moved upwardly in switch closing direction and while the actuating toggle formed by the link 17 and the lever 20 is being straightened, the thrust exerted through the operating arm 24 positively locks the handle to the switch mechanism with no possibility of disengagement during the major portion of the switch closing movement. When the handle has substantially completed its movement and just as the switch contacts are about to come into engagement the connection between the handle and the movable member 17 is so set that it tends to collapse as a result of the thrust between the mechanism and the handle, and is therefore very sensitive. This change in sensitiveness of the normally positive connection is brought about by the pin 26 on arm 24 engaging two cam-shaped members 31, which move the roller 27 far enough so that, as a result of its pressure upon the surface 23, it now tends to move away from the stops or lugs 30 instead of toward them. This result follows from the cams 31 moving the roller to the other side of the perpendicular from the plane surface 23 through the pivot of the member 24. The total collapse of the connections at this time is prevented and the roller is kept in engagement with the plane surface by some suitable restraining means which prevents further movement of the roller along the plane surface as long as conditions are normal, but automatically permits such movement when abnormal conditions appear. The particular restraining means shown comprises a latch 32 mounted on a pivot 33 and extending downwardly to a point immediately above and in front of the plane surface of the lever 20 when the same is moved to the position corresponding to the closed position of the switch. The latch 32 is held in this position by a spring 34, which forces a finger 35 on the latch against a stop 36 projecting from the escutcheon plate. In order that the latch may automatically release the roller 27 and permit it to move out of engagement with the surface 23 of the lever 20, the latch is provided with a laterally ex-

tending arm or finger 37, which co-operates with a suitable electroresponsive or electro-magnetic tripping device. The tripping coils, which I have here illustrated as the 5 electromagnetic means for tripping the switch and indicated by the reference numeral 38, are provided with movable cores 39 having laterally extending tripping pins 40. In order to move the latch 32 automatically, I provide a tripping bar 41 mounted on pivots 42, and extending across the escutcheon plate. This tripping bar is provided at either end with fingers 43 which extend around the cores of the tripping 10 coils and are adapted to be engaged by the pins 40 of the cores when either of the tripping coils is operatively energized. The tripping bar is also provided with a finger 44 which is adapted to engage the finger 37 15 on the latch 32. When either of the coils 38 is energized, the corresponding core is lifted and its pin 40 engages the corresponding fingers 43, thus rotating the tripping bar about the pivot 42, whereupon the finger 44 20 engages the finger 37 of the latch 32 and removes the lower end of the latch from the path of the roller 27. This movement of the latch leaves the roller free to move along the surface 23 until it is free of the member 20, 25 as shown in Fig. 3, whereupon the arm 20 is free to move and the switch automatically opens.

The operating handle is maintained in switch closing position by means of a latch 35 45 which is pivoted to the escutcheon plate at 47 and extends through a slot 46 in the handle. The latch is urged upwardly by a spring 48, its upward movement being limited by a stop 49 on the latch which engages 50 a projection on the escutcheon plate. A pin 50 extends laterally through the operating handle and the slot 46 in such a position as to engage either of the two notches 51 or 52 in the latch 45 corresponding to the full line 55 position and the dotted line position of the handle in Fig. 3. The operating handle is provided with a hand latch 53 having a portion 54 extending above the handle and a head 55 for disengaging the latch 45 from the pin 50.

The operation of the device is as follows: When the switch opens, the movable member 5 in Fig. 4. In order to close the switch, it is necessary to move the handle or operating lever B from the position shown in Fig. 3 through substantially 180 degrees and into the position shown in Fig. 4. Now, when the handle is moved upwardly the roller 27 engages the plane surface 22 in the manner heretofore indicated so as to positively lock the operating handle B to the switch mechanism. The upward movement of the handle 10 then swings the lever 20 around its pivot

and moves the member 17 to the right to close the switch. Now, when the handle has substantially completed its movement, the pin 26, on which the roller 27 is mounted, engages the cams 31 and the energy furnished by the operator is utilized to move the roller to the other side of the perpendicular. At this time, the latch 32 prevents extensive upward movement of the roller along the surface 23, so that total collapse of the connection cannot occur until the relation of the latch and roller is changed. The connection is now very sensitive to the action of the tripping coils, and when either of these coils is energized the latch 32 is readily 70 moved so as to free the roller 27 and permit the switch to open. 75

In order to make the switch quick opening and at the same time protect the operator against injury, my invention provides means 80 for removing the operation of the switch from the control of the operator upon an initial switch opening movement of the operating handle. By referring to Fig. 3, it will be seen that as the handle moves toward the dotted line position, the roller 27 is moved to the left sufficiently to remove the same from operative engagement with the latch 32, whereupon the handle is disconnected from the switch and the switch is free 90 to open at the same speed as when automatically tripped by the electromagnets 38. At the same time the operator is not liable to injury by the handle, as would be the case if the handle were rigidly connected to the 100 switch mechanism, as in that case the handle would be swung outward and downward with the great speed and force resulting from the action throughout its entire movement of the weight of the movable parts of the 105 switch.

While I have illustrated my invention in connection with an oil switch and in a three-phase system, it will, of course, be understood that my invention is not limited to a 110 switch of this character nor to such a system.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:

1. An electric switch comprising an operating handle, a movable switch member, a non-latching connection between said handle and said switch member comprising two 125 members held in abutting engagement and normally slightly overset during movement of said handle in the switch closing direction, means for undersetting said abutting members as the switch is closed, and re- 130

- straining means mounted adjacent said abutting members to normally hold them in abutment as long as the switch is closed, said members being separable from each other
- 5 during the initial movement of said operating handle in switch opening direction and thereby allowing said switch to open free from said handle.
2. An electric switch comprising a switch
- 10 actuating mechanism, an actuating lever having a plane engaging surface and operatively related to said actuating mechanism, an operating member, an operating arm mounted on said operating member and provided with a roller engaging surface adapted to coöperate with the plane engaging surface of said actuating lever to form therewith a connection between said operating member and said actuating mechanism, said connection being held rigid to move said actuating mechanism into switch closing position in response to the movement of said operating member in switch closing direction, means for moving said roller engaging surface along said plane engaging surface to partially collapse said rigid connection during the final closing movement of said operating member, and restraining means acting on said operating arm to normally prevent the complete disengagement of said coöperating surfaces, said roller engaging surface being movable beyond said plane engaging surface to collapse said connection in response to the initial movement of said operating member in switch opening direction whereby said actuating mechanism moves into switch opening position while said operating member remains in substantially switch closing position.
- 15 3. In an electric switch, the combination with a switch actuating mechanism, of an operating member for said mechanism, an actuating lever provided with a plane surface and a link operatively connected to said lever to form therewith an actuating toggle, an arm mounted on said operating member and biased to engage the plane surface of said lever during the movement of said operating member in switch closing direction
- 20 in a line through the pivot of said arm perpendicular to said surface, said actuating toggle moving said switch actuating mechanism thereby into switch closing position, means operative during the final closing
- 25 movement of said operating member for moving said arm out of the said perpendicular alignment, restraining means biased to hold said arm in engagement with said lever while the switch is closed, and means for releasing said restraining means to allow said actuating toggle and said actuating mechanism to move independently into switch opening position while said operating member remains in substantially switch closing position.
- 30 4. In an electric switch, the combination with a switch actuating mechanism, of an actuating toggle comprising an actuating lever having a plane surface and a link pivoted thereto and operatively related to said actuating mechanism, an operating member, an arm mounted on said operating member and coöperating with the plane surface of said actuating lever to form a separable connection between said operating member and said actuating mechanism, means for holding said arm in thrust transmitting relation with the plane surface of said lever for rendering said separable connection operative to move said switch actuating mechanism in response to the movement of said operating member in switch closing direction, means for moving said arm along the plane surface of said lever during the final closing movement of said operating member, and a latch coöperating with said arm to prevent said arm from moving out of engagement with the plane surface of said lever while the switch is closed, said latch being rendered inoperative to hold said arm in engagement with the surface of said lever either upon the occurrence of abnormal conditions on the circuit through the switch or in response to a movement of said operating member in switch opening direction whereby said actuating mechanism moves independently into switch opening position while said operating member remains in substantially switch closing position.
- 35 5. An operating mechanism for an electric switch comprising an operating lever, an actuating lever provided with a plane surface, a link coöperating with said actuating lever to form an actuating toggle, an operating arm mounted on said operating lever and biased in a position to engage the plane surface of said actuating lever in a line perpendicular to said surface in response to a movement of said operating lever in switch closing direction, said operating arm and said actuating lever forming thereby a rigid connection for transmitting the thrust of said operating lever and causing the switch to close, means for moving said arm out of said perpendicular alignment with said plane surface during the final closing movement of said operating lever, and a latch biased in a position to prevent said operating arm from moving out of engagement with said plane surface while said switch is closed, said operating arm being withdrawn from said latch in response to the initial movement of said operating lever in switch opening direction and thereby causing said actuating lever to move free from said operating arm into switch opening position while said operating lever remains in substantially switch closing position.
- 40 6. The combination with a switch actuat-

ing mechanism for an electric switch of an operating mechanism comprising an operating lever, a link operatively related to said actuating mechanism, a connection between 5 said operating lever and said link for transmitting the thrust of said operating lever to said actuating mechanism, said connection comprising two non-latching members having dissimilar engaging surfaces 10 moving into direct thrust transmitting position in response to the movement of said operating lever in switch closing direction, means for moving said connection out of said direct thrust transmitting position during the final closing movement of said operating lever, and restraining means for normally preventing the disengagement of said members, said restraining means allowing said members to separate in response to 15 the initial movement of said operating lever in switch opening direction whereby said actuating mechanism moves independently to open the switch while said operating lever remains in substantially switch closing 20 position.

7. The combination with a switch actuating mechanism, of an operating member, an actuating lever provided with a plane surface, lugs on said operating member, an 5 arm mounted on said member and normally biased into engagement with said lugs, said arm being movable into engagement with the plane surface of said actuating lever to transmit the thrust of said operating member as said member is moved in switch 10 closing direction, a cam-shaped member for moving said arm out of engagement with said lugs and into a non-thrust transmitting position during the final closing movement 15 of said switch, and a latch mounted to engage said arm and prevent it from moving out of engagement with the plane surface of said lever while the switch is closed, said latch being inoperative to hold 20 said arm during the initial movement of said operating member in switch opening direction, whereby said switch opens free from said operating member.

8. An operating mechanism for an electric switch comprising an operating member, an actuating lever provided with a plane surface, lugs on said operating member, an arm mounted on said member and normally biased to engage said lugs and in 5 a position to engage the plane surface of said actuating lever to transmit the thrust of said operating member as said member moves in switch closing direction, a cam-shaped member to displace a movement of 10 said arm in the direction of the out of engagement with said lugs and to engage the plane surface of said actuating lever during the final closing movement of said operating member, a link moved into position 15 to engage said arm and prevent it from 20 moving out of engagement with said plane surface as the switch is closed, latching means for holding said operating member in switch closing position, and a tripping member for moving said latch out of the 25 path of said arm and allowing said actuating lever to move free from said arm into switch opening position.

9. In an electric switch, the combination with an actuating mechanism therefor, and 75 an operating lever, of a non-latching connection between said lever and said mechanism comprising members having abutting engaging surfaces movable into a thrust transmitting relation in response to the 80 movement of said operating lever in switch closing direction, means for maintaining the abutting surfaces of said members in said thrust transmitting relation during the closing of the switch, means for moving the 85 abutting surfaces of said members into a non-thrust transmitting relation during the final closing movement of said operating lever, and means for holding said connection in said non-thrust transmitting relation 90 while the switch is closed, said abutting surfaces being separable in response to the initial movement of said operating lever in switch opening direction to cause the opening of said switch independent of said operating lever and while said lever is substantially in switch closing position.

10. In an electric switch, the combination with an actuating mechanism therefor, and an operating lever, of means for moving 100 said actuating mechanism into switch closing position in response to the movement of said operating lever and for moving said actuating mechanism into switch opening position independent of said operating lever, comprising an operating arm carried by said operating lever and having an engaging surface, an actuating lever carried by said actuating mechanism having a dissimilar cooperating engaging surface, the 110 engaging surface of said operating arm being movable into abutting engagement with the engaging surface of said actuating lever to form a thrust transmitting connection between said operating lever and said 115 actuating mechanism as said operating lever is moved toward switch closing position, means for moving the engaging surface of said operating arm along the engaging surface of said actuating lever during the final 120 closing movement of said operating lever to form a non-thrust transmitting connection, and means for maintaining said operating arm and said actuating lever as a non-thrust transmitting connection while the switch is 125 closed, the engaging surface of said operating arm being movable out of abutting engagement with the surface of said actuating lever to cause the collapse of said connection either at will or in response to the 130

initial movement of said operating lever to switch opening position.

11. In an electric switch, the combination with an actuating mechanism therefor, and 5 an operating lever, of an intermediate mechanism, comprising an operating arm carried by said lever having a roller engaging surface, an actuating lever carried by said actuating mechanism having a coöperating 10 plane engaging surface, said operating arm being movable to carry its roller engaging surface into thrust transmitting engagement with the plane surface of said actuating lever in response to the movement of said operating lever in switch closing direction, means for holding 15 said roller engaging surface in thrust transmitting engagement during the closing of the switch, a cam shaped

member for moving said operating arm and carrying its roller engaging surface along 20 the plane surface of said operating arm into non-thrust transmitting engagement therewith during the final closing movement of 25 said operating lever, and means for holding said engaging surfaces in non-thrust transmitting engagement while the switch is closed, said surfaces being disengaged in response to the initial movement of said operating lever in switch opening direction.

In witness whereof, I have hereunto set 30 my hand this 17th day of March, 1913.

HARRY M. STEVENS.
